WELL CASING

James Daniel Tennison, Memphis, Tenn.

Application November 5, 1951, Serial No. 254,948

6 Claims. (Cl. 138—74)

This invention relates to tubular conduits and more particularly to a sheet metal well casing which may be supplied in sections and coupled together to form a casing of any desired length.

Heretofore many types of sheet metal well casings or other conduits have been proposed but these have been subject to numerous disadvantages such as inability to form a tight joint between adjacent sections often resulting in dropping a lower section into a well where it is not recoverable. These prior casings have also been provided with ends which are relatively weak and which have therefore been subject to damage such as bending thus materially increasing the difficulties with which adjacent sections are joined. Likewise these prior art structures have been provided with seams which fail to prevent undue expansion and contraction of the casing thus further contributing to the difficulties experienced in assembling adjacent sections to provide a relatively tight joint therebetween.

It is therefore an object of the present invention to provide a sheet metal conduit having threaded ends which may be joined with adjacent sections to provide a casing or conduit of any desired length and in which the joint is relatively tight thus preventing inadvertent separation of adjacent sections.

Another object of the invention is to provide a sheet metal conduit or well casing in which the seam extends throughout the threaded sections of the conduit and in which such seam precludes expansion or contraction of the conduit at the threaded sections.

Another object of the invention is to provide a sheet metal conduit or well casing in which the seam at the threaded sections is formed in such a manner as to present a relatively smooth external surface on the male section and a relatively smooth internal surface on the female section.

A further object of the invention is to provide a sheet metal conduit or well casing in which the thread on the female portion of the casing terminates at its inner end in an internal shoulder the plane of which is substantially perpendicular to the axis of the casing, and in which insertion of the male portion of the conduit terminates at this shoulder and presents a relatively smooth inner surface.

A still further object of the invention is to provide a sheet metal conduit or well casing in which the thread at each end of the casing is formed in such a manner as to impart the utmost strength thereto.

Further objects and advantages of the invention will be apparent from the following description taken in conjunction with the accompanying drawings, wherein:

Fig. 1 is an elevational view showing a sheet metal conduit or well casing constructed in accordance with this invention;

Fig. 2 a sectional view taken on the line 2—2 of Fig. 1;

Fig. 3 a sectional view taken on the line 3—3 of Fig. 1;

2

Fig. 4 a sectional view taken on the line 4—4 of Fig. 1; and

Fig. 5 is a fragmentary sectional view showing adjacent sections of sheet metal conduit or well casing constructed in accordance with this invention and in assembled relationship.

With continued reference to the drawing, there is shown a well casing or conduit 10 constructed of sheet metal and in which the casing tapers from one end to the other. As viewed in Fig. 1 the taper is from left to right. Casing 10 is provided with a longitudinal lock seam 11 which serves to retain the body 12 of the casing located between the threaded ends thereof in assembled cylindrical relationship this lock seam being shown in Fig. 3. The lock seam 11 may if desired be soldered or welded together but such additional fastening means is not necessary to the operation of the invention.

As shown in Fig. 1 the body 12 of the casing 10 terminates at the left hand end of Fig. 1 in a female threaded section 13 and at the right hand end of Fig. 1 in a male threaded section 14. The threads may be formed in the casing 10 by rolling or other equivalent metal working operations and these threads provide inwardly and outwardly extending corrugations appearing as a sine wave in a longitudinal cross section of a thread which serve to materially strengthen the ends of the casing. This formation of the threads serves in a large measure to prevent inadvertent damage and distortion to the ends of the casing and thus materially facilitates assembly of a plurality of sections to provide an elongated casing of any desired length.

An inspection of Figs. 1 and 5 will show that the female thread 13 terminates at the inner end in an internal shoulder or annular bead 15, the plane of which is substantially perpendicular to the axis of the casing 10. The remainder of the thread 13 is of course helical and may be of any desired pitch. The male thread 14 is conventional and the end 16 of the casing is cut perpendicular to the axis of the casing.

The lock seam 11 which serves to retain the body 12 of the casing 10 together terminates adjacent the inner end of the female thread 13 and male thread 14 and from this point on the seam becomes a lap seam shown at 17 in Fig. 2 and 18 in Fig. 4. As will be noted from an inspection of Fig. 2 lap seam 17 is offset to present a substantially smooth inner surface in order to facilitate engagement of the male threads with the female threads 13. Likewise the lap seam 18 as shown in Fig. 4 is offset to present a relatively smooth outer surface in order that these male threads 14 may engage and smoothly rotate within the female threads 13 of an adjacent casing section. In order to prevent separation or collapsing of the casing at the threaded sections 13 and 14 the lap seams 17 and 18 may be additionally secured by spot welds 19 and 20.

In operation a male thread 14 of one casing section is inserted and turned into a female thread 13 of another casing section and as will be seen from an inspection of Fig. 5, the end 16 of the male thread 14 advances within the female thread 13 until the end 16 reaches the shoulder 15 at which time since the female thread terminates at this point insertion of the male thread ceases and the two sections are tightly joined together. Any relative movement beyond this point is impossible and consequently further relative rotation will be prevented and the operators will understand that a tight firm joint has been completed. Also during this operation the provision of the spot welds 19 and 20 on the lap seams 17 and 18 will prevent expansion or collapse of the material of the casing 10 in the vicinity of the joint and will further contribute to the provision of a tight firm joint between the sections.

It will be seen that by the above described invention

there has been provided a relatively simple screw threaded joint to be utilized between adjacent sections of a sheet metal casing and in which assembling of adjacent sections is facilitated by a joint which permits relative rotation and insertion of one section into the other a predetermined distance at which time a firm tight joint is established, and further a construction in which any expansion or collapsing of the material of the casing at the joint is prevented. The particular formation of the threads which are utilized to form the joint also prevent mutilation or bending of the threads of the casing at this point and therefore materially contribute to the efficient and rapid assembly of sections to form a casing of the desired length.

It will be obvious to those skilled in the art that various changes may be made in the invention without departing from the spirit and scope thereof and therefore the invention is not limited by that which is shown in the drawings and described in the specification, but only as indicated in the appended claims.

What is claimed is:

1. A sheet metal conduit comprising a tapered one-piece body having a lock seam terminating intermediate the extremities thereof, a female threaded section on the large end of said conduit and a male threaded section on the small end of said conduit, a spot welded lap seam in each threaded section, the lap seam in said female section being offset outwardly to provide a relatively smooth inner surface and the lap seam in said male section being offset inwardly to provide a relatively smooth outer surface whereby a male and female section may be threaded together without interference, said female thread terminating at its inner end in an annular internal shoulder the plane of which is substantially perpendicular to the axis of said conduit whereby upon threaded engagement of said male section with said female section the end of said male section will abut said shoulder and prevent further inward relative movement and provide a tight joint.

2. A sheet metal conduit comprising a tapered one-piece body having a seam terminating intermediate the extremities thereof, a female threaded section on the large end of said conduit and a male threaded section on the small end of said conduit, a spot welded lap seam in each threaded section, the lap seam in said female section being offset outwardly to provide a relatively smooth inner surface and the lap seam in said male section being offset inwardly to provide a relatively smooth outer surface whereby a male and female section may be threaded together without interference, said female thread terminating at its inner end in an annular internal shoulder the plane of which is substantially perpendicular to the axis of said conduit whereby upon threaded engagement of said male section with said female section the end of said male section will abut said shoulder and prevent further inward relative movement and provide a tight joint.

3. A sheet metal conduit comprising a tapered one-piece body having a seam terminating intermediate the extremities thereof, a female threaded section on the large end of said conduit and a male threaded section on the small end of said conduit, a lap seam in each threaded section, the lap seam in said female section being offset outwardly to provide a relatively smooth inner surface and the lap seam in said male section being offset inwardly to provide a relatively smooth outer surface whereby a male and female section may be threaded together without interference, said female thread terminating at its inner end in an annular internal shoulder the plane of which is substantially perpendicular to the axis of said conduit whereby upon threaded engagement of said male section with said female section the end of said male section will abut said shoulder and prevent further inward relative movement and provide a tight joint.

5. A sheet metal conduit comprising a one piece body having a seam terminating intermediate the extremities thereof, a tapered female threaded section on one end of said conduit and a tapered male threaded section on the opposite end of said conduit, a spot welded lap seam in each threaded section, the lap seam in said female section being offset outwardly to provide a relatively smooth inner surface and the lap seam in said male section being offset inwardly to provide a relatively smooth outer surface whereby a male and female section may be threaded together without interference, said female thread terminating at its inner end in an annular internal shoulder the plane of which is substantially perpendicular to the axis of said conduit whereby upon threaded engagement of said male section with the female section of an adjacent conduit the end of said male section will abut said shoulder and prevent further inward relative movement and provide a tight joint.

10. A sheet metal conduit comprising a one piece body having a seam terminating intermediate the extremities thereof, a tapered female threaded section on one end of said conduit and a tapered male threaded section on the opposite end of said conduit, a spot welded lap seam in each threaded section, the lap seam in said female section being offset outwardly to provide a relatively smooth inner surface and the lap seam in said male section being offset inwardly to provide a relatively smooth outer surface whereby a male and female section may be threaded together without interference, said female thread terminating at its inner end in an annular internal shoulder the plane of which is substantially perpendicular to the axis of said conduit whereby upon threaded engagement of said male section with the female section of an adjacent conduit the end of said male section will abut said shoulder and prevent further inward relative movement and provide a tight joint.

15. A sheet metal conduit comprising a one piece body having a seam terminating intermediate the extremities thereof, a tapered female threaded section on one end of said conduit and a tapered male threaded section on the opposite end of said conduit, a spot welded lap seam in each threaded section, the lap seam in said female section being offset outwardly to provide a relatively smooth inner surface and the lap seam in said male section being offset inwardly to provide a relatively smooth outer surface whereby a male and female section may be threaded together without interference.

20. A sheet metal conduit comprising a one piece body having a seam terminating intermediate the extremities thereof, a tapered female threaded section on one end of said conduit and a tapered male threaded section on the opposite end of said conduit, a spot welded lap seam in each threaded section, the lap seam in said female section being offset outwardly to provide a relatively smooth inner surface and the lap seam in said male section being offset inwardly to provide a relatively smooth outer surface whereby a male and female section may be threaded together without interference.

25. A sheet metal conduit comprising a one piece body having a seam terminating intermediate the extremities thereof, a tapered female threaded section on one end of said conduit and a tapered male threaded section on the opposite end of said conduit, a spot welded lap seam in each threaded section, the lap seam in said female section being offset outwardly to provide a relatively smooth inner surface and the lap seam in said male section being offset inwardly to provide a relatively smooth outer surface whereby a male and female section may be threaded together without interference.

30. A sheet metal conduit comprising a one piece body having a seam terminating intermediate the extremities thereof, a tapered female threaded section on one end of said conduit and a tapered male threaded section on the opposite end of said conduit, a spot welded lap seam in each threaded section, the lap seam in said female section being offset outwardly to provide a relatively smooth inner surface and the lap seam in said male section being offset inwardly to provide a relatively smooth outer surface whereby a male and female section may be threaded together without interference.

35. A sheet metal conduit comprising a one piece body having a seam terminating intermediate the extremities thereof, a tapered female threaded section on one end of said conduit and a tapered male threaded section on the opposite end of said conduit, a spot welded lap seam in each threaded section, the lap seam in said female section being offset outwardly to provide a relatively smooth inner surface and the lap seam in said male section being offset inwardly to provide a relatively smooth outer surface whereby a male and female section may be threaded together without interference.

40. A sheet metal conduit comprising a one piece body having a seam terminating intermediate the extremities thereof, a tapered female threaded section on one end of said conduit and a tapered male threaded section on the opposite end of said conduit, a spot welded lap seam in each threaded section, the lap seam in said female section being offset outwardly to provide a relatively smooth inner surface and the lap seam in said male section being offset inwardly to provide a relatively smooth outer surface whereby a male and female section may be threaded together without interference.

45. A sheet metal conduit comprising a one piece body having a seam terminating intermediate the extremities thereof, a tapered female threaded section on one end of said conduit and a tapered male threaded section on the opposite end of said conduit, a spot welded lap seam in each threaded section, the lap seam in said female section being offset outwardly to provide a relatively smooth inner surface and the lap seam in said male section being offset inwardly to provide a relatively smooth outer surface whereby a male and female section may be threaded together without interference.

50. A sheet metal conduit comprising a one piece body having a seam terminating intermediate the extremities thereof, a tapered female threaded section on one end of said conduit and a tapered male threaded section on the opposite end of said conduit, a spot welded lap seam in each threaded section, the lap seam in said female section being offset outwardly to provide a relatively smooth inner surface and the lap seam in said male section being offset inwardly to provide a relatively smooth outer surface whereby a male and female section may be threaded together without interference.
